UNITED STATES PATENT OFFICE.

CHARLES A. FRENCH, OF CHICAGO, AND GUSTAF W. ENGSTROM, OF RIVERSIDE, ILLINOIS, ASSIGNORS TO INTERNATIONAL HARVESTER COMPANY, A CORPORATION OF NEW JERSEY.

SEMIFLASH BOILER.

Application filed November 11, 1920. Serial No. 423,271.

Our invention relates to steam boilers and particularly to semi-flash boilers adapted for use with motor cars, trucks, tractors and the like.

6 The flash and semi-flash boilers commonly used in the generation of steam for the operation of motor cars comprise generating and superheating coils or tubes which are in direct communication so that the steam passes directly from the generating zone to the superheating zone, in fact, the two zones form one continuous zone which is divided into generating and superheating areas that are continuously changing in relative size with the 10 variations in the demands for steam made on the boiler and the rate of steaming. This has been found very unsatisfactory, since the superheating zone will be the largest and the resultant degree of superheat the greatest 15 when the load and demand for steam are lightest, and conversely, when the load is greatest and a large degree of superheat is desired, the superheating area decreases, with the result that wet steam will be delivered to 20 the engine and in some instances slugs of water have been carried over with consequent 25 injury to the engine.

In such boilers the superheater is usually located in the hottest part of the path of 30 the gases from the furnace or burner, which results in burning the tubes of the superheater when the boiler is steaming slowly, and necessitates their renewal at frequent intervals.

35 The tubes or coils are commonly secured by welding or by special joints to headers or tube sheets exposed to the flame and hot gases from the burner. The expansion and contraction at the welds or joints causes leakage which soon becomes excessive and greatly reduces the efficiency of the boiler and is the cause of frequent lay-up for repairs.

40 Another objection to boilers of this character has been the inability to prevent formation of scale in the vaporizing coils or tubes and the impossibility of removing the scale after it has been formed because of the small size of the tubes.

Having the above noted defects in mind, 45 we have invented a boiler that is free from all of these faults and which has among its many objects to provide a boiler having pre-heating, evaporating, and superheating zones

of fixed heating surface and bearing a fixed ratio to the burner.

Another object is to provide a boiler in which water cannot enter the superheating zone or coils, thereby absolutely preventing priming.

60 A further object is to provide a boiler in which there are no joints between tubes and headers or tube sheets exposed to the hot gases, but only coils, so that expansion and contraction can have no harmful effect.

A still further object is the provision of a boiler having a high rate of circulation in the vaporizing coils, thereby preventing the formation and deposit of scale.

65 Yet another object is the provision of a boiler having the evaporating zone wherein the greatest amount of heat must be absorbed to generate the steam located in the hottest part of the boiler.

70 Other important objects are to provide a boiler in which the water level may vary between wide limits without variation in the water level in the evaporating coils or the quantity of water supplied thereto; to provide a boiler in which the superheater is 75 protected from the hottest gases from the burner; and, to provide a boiler having means dependent on pressure conditions in the boiler and rate of utilizing steam for controlling the amount of fuel supplied to the 80 burner.

85 The above and other objects will be apparent to those skilled in the art and are attained in the embodiment of our invention hereinafter described and illustrated in the 90 accompanying drawings in which—

95 Fig. 1 is a sectional view of one form of our improved boiler, the control means for the burner being shown diagrammatically.

Fig. 2 is a sectional view of a modified 100 form of our invention, the control means being omitted for the sake of clearness.

105 Referring to Fig. 1, 3 indicates the boiler housing or casing having its top closed by a burner 4, which is hollow or cored out at 6 to provide a vaporizing chamber for the fuel sprayed from the nozzle 7 into the passage 8 leading from the fan or blower 9. The vaporized fuel and air pass from the chamber 6 to the burner tubes 10, which are provided with fine slots or perforations through which the vaporized fuel and air

issue and burn. The hot gases pass vertically downward and around the coils constituting the evaporating, superheating and preheating zones, the filler 11 serving as a spreader 5 for the flame and causing the hot gases to pass around and through the coils. After giving up their heat to the coils, the waste products of combustion are discharged through the flue 12. The passage of fuel through the nozzle 7 is controlled by a needle valve 13 and the air is controlled by a throttle valve 14 connected to the pressure operated regulators 15 and 16, as will presently be described.

In the embodiment of our invention shown 15 in Fig. 1 we employ ten coils of which the four lower coils 17 constitute the preheating zone, the three upper coils 18 the evaporating zone, and the three intermediate coils 19 the superheater. It will of course be 20 understood that this number of coils is but illustrative of our invention and that both the total and relative numbers of coils in the different zones may be changed as desired.

Feed water from the condenser enters the 25 lower coil through the pipe 20, passes upwardly through the successive coils 17 and is discharged through pipe 21 into the storage drum 22. The pump 24 draws hot water from the drum and discharges it under increased pressure to the pipe 25 from which 30 it passes into the lower coil 18 and is transformed into steam as it passes upward through the coils. The steam leaves the coils 18 through the pipe 26 which discharges tangentially into the drum 22 above the water level. The tangential discharge of the steam into the drum causes centrifugal separation of any moisture that the steam may contain so that only dry saturated steam will enter 35 the steam pipe 27 and the superheating coils 19 to which it leads. Superheated steam leaves the coils 19 through the pipe 28 and passes through the heat exchange element 29 provided with the baffles 30 which cause the 40 steam to take a tortuous passage through the Monel or copper slugs with which the heat exchanger is filled. The object of the heat exchange element is to equalize the superheat by absorbing any excess that the steam 45 may contain and later giving it up if the operating conditions of the boiler should cause the degree of superheat to fall below normal. The heat exchanger insures an even degree of superheat in the steam delivered to the engine through the pipe 31.

It is to be particularly noted that the passage of the hot gases through the boiler is 50 directly opposed to the direction of the passage of the water and steam in all of the zones, and that the hot gases first encounter the evaporating coils where by far the greatest amount of heat must be given up to convert the water into steam. After passing over the evaporating coils, the hot gases, with 55 their temperature diminished below the point

at which the coils would be injured but still sufficiently above the temperature of saturated steam to impart the desired degree of superheat thereto, continue their downward passage and encounter the superheating coils 70 19 and give up more of their heat to superheat the steam. The gases then pass over the pre-heating coils 17 and after giving up heat to the water therein leave the boiler through the stack or flue 12 at a comparatively low temperature, which we have found in practice does not exceed 250° F. 75

Returning to the fuel and air controlling means, the regulator is provided with a diaphragm 32, one side of which is subjected to boiler pressure in the drum, 22 through the connecting pipe 33. A rod 34 contacts with the other side of the diaphragm and is connected to the needle valve 13 and throttle valve 14 by the links and levers illustrated. The boiler and drum are designed to operate under a normal pressure of 500 lbs. per square inch, and when this or a lower pressure exists in the drum 22, the valves 13 and 14 will be fully open, but as the pressure increases, the rod 34 will be actuated to reduce the valve openings and at 600 lbs. pressure per square inch both valves will be fully closed. 90

The regulator 16 has a diaphragm 36, one side of which is connected to the intake side of the pump 24 by pipe 37 and the other side connected to the discharge side of the pump by pipe 38. A rod 39 actuated by changes in pressure on the two sides of the diaphragm is connected to the valves 13 and 14 in the same manner as rod 34. In the normal operation of the boiler, the pump draws water from the drum 22 and forces it through the evaporating coils at a high speed, the velocity of the water entering the coil being approximately 500 feet per minute, and that of the steam leaving the coil and entering the drum being 12,000 to 20,000 feet per minute; a difference in pressure of 50 to 100 lbs. per square inch between the intake and discharge sides of the pump being required to do this. When the pump is receiving water from the drum this difference in pressure exists on the two sides of the diaphragm 36 and the valves 13 and 14 are held open, but if the supply of water in the drum fails or the pump fails to feed water to the evaporating coils for any reason, the pressure will be equalized on the two sides of the diaphragm and the valves 13 and 14 will be closed. 110

It will thus be seen that we have provided means for keeping the pressure substantially constant in our boiler under all loads since the valves 13 and 14 will be partially closed by the increase in steam pressure when the boiler is steaming slowly under a light demand for steam and correspondingly opened to generate more steam as the demand for steam in- 125 130

creases. The regulator 16 serves as a safety device to prevent burning of the evaporating coils if the supply of water fails. It is to be noted that the water level in the drum 22 may vary from a maximum at the height of the pipe 26 to a minimum at the pump intake level without affecting the operation or steaming qualities of the boiler. We consider this a very important part of our invention, since it enables the boiler to operate under widely varying loads, without changing the total amount of water in circulation in the system.

The modification of our boiler shown in Fig. 2 has the same general features but differs in the structure of details and arrangement of parts, the principal differences lying in the location and type of burner, the arrangement of coils, and housing of the storage drum, coils and burner within a single casing.

A blower 50 and fuel pipe 51 co-operate to supply air and fuel to the vaporizing drum 52 of the burner, the mixture entering the drum tangentially so that centrifugal separation will keep the unvaporized fuel against the outer portion of the drum and the heated and thoroughly vaporized mixture at the center. The burner proper consists of two cylindrical sections 53 and 54 which are in open communication with the center of the drum 52 at the top and bottom respectively. The side walls of the sections are finely perforated and the mixture burns as it issues therefrom. Flame from the lower section 54 passes radially outward and then upward about the drum 52, heating and vaporizing the fuel mixture therein. The gases then pass upward and mingle with the gases from the main burner section 53.

A pilot burner 55 is used to initially heat the drum 52 and receives its fuel under pressure from the coil 56. The coil 56 extends outside the burner casing and has a starting coil 57 within a heating cup 58, the coil then re-enters the casing and discharges into the ejector 59 where it picks up sufficient air to form a combustible mixture which enters the pilot burner tangentially. In starting the boiler, a quantity of volatile fuel such as gasoline, is supplied to the cup 58 sufficient to vaporize the fuel in the coil 57. As this fuel becomes vaporized it enters the pilot burner mixed with air where it is ignited. When the drum 52 becomes heated, the vaporized mixture issuing from the burner sections 53 and 54 will be ignited, the section 54 being ignited from the pilot burner, and the section 53 being ignited by flame following the perforations 60 in the pipe 61 connecting the sections 53 and 54 on opposite sides of the drum 52.

The preheating, superheating and evaporating coils in Fig. 2 surround the burner 53 so that the path of the hot gases is radially outward through the coils instead of longi-

tudinal as in Fig. 1. Specifically, these coils comprise separate, horizontally or radially spaced, vertical banks of evaporator, superheater, and preheater coils, each bank comprising superposed, helical coils lying in substantially horizontal confines with and surrounding the burner.

The feed water pipe 63 leads water from a condenser to the three outer banks of coils 64 which constitute the pre-heater. The flow of water is upward in the outer coil, then down in the second coil and upward through the third coil, thence to the storage drum 65 through pipe 66. The circulating pump 67 draws water from the drum through intake pipe 68 and discharges it under increased pressure through pipe 69 and evaporating coils 70. The evaporating zone consists of the two inner banks of coils 70 and a flat coil continuous therewith and bridging the annular space between the burner and inner coils. The steam generated in the coils 70 issues tangentially into the storage drum through the pipe 71 above the water line. Dry steam is taken from the top of the drum by the steam pipe 72 and after passing through the superheating coils 73 is led through pipe 74 to the engine or other prime mover. Thus, it is seen that the evaporator coils have water delivered to them under increased pressure, by the pump 67 drawing water from the storage and separating drum 65. This increased water supply increases the heat absorbing capacity of the evaporator coils thereby to protect said coils and also further to protect the superheater coils and to increase the rate of steam generation in said evaporator coils.

The waste gases after passing radially outward from the burner and around the coils pass upward into annular space 75 in the dome shaped chamber 76 through perforations or openings 76' near the periphery of the upper wall 77 of the casing 78 housing the coils and burner. The storage drum 65 is housed within the casing at this point so that it is surrounded by the waste gases which have a temperature considerably above that of the atmosphere and enclosed within the insulating lining 75'. This enables us to reduce the radiation loss from the drum and also to use less heat insulation or lagging thereon. The waste gases are finally discharged through the stack 79.

We have shown the superheater coils of slightly greater diameter in Fig. 2, than the tubes of the preheating and evaporating coils, which we have found to be advantageous in that it permits the steam to expand in the superheating coils as its temperature increases without increasing its velocity and also enables us to use fewer coils in the superheater by reason of the lower velocity of the steam. We have not shown the regulators 15 and 16 and heat exchanger 29 in

Fig. 2, but it is to be understood that they are adapted for use with this form of boiler as well as that shown in Fig. 1 and are omitted only to avoid needless repetition 5 and complications in the drawings. While we have shown the tubes of the preheating superheating and evaporating coils of the same diameter in Fig. 1, they may be of any relative diameters found necessary to 10 secure the desired rate of flow of fluid in the coils, rate of steaming of the boiler and degree of superheat.

Having thus described our invention, what we claim as new and desire to secure by Letters Patent is:

1. In a steam generator, the combination of a burner, a casing, a superheater of fixed heating surface, an evaporator of fixed heating surface, a preheater of fixed heating surface, the superheater, evaporator and preheater all surrounding the burner, a storage drum, means for supplying water to the preheater, a connection for discharging the water from the preheater into the drum, a single connection for taking the water from the drum and delivering it to the evaporator, a pump in said single connection for forcing the water through the evaporator, a connection for delivering water and steam from 25 the evaporator back to the drum above the center thereof, and a connection from the top of the drum for delivering the steam to the superheater.

2. In a boiler, the combination of a casing, a burner discharging hot gases of combustion thereinto, an evaporating coil adjacent the burner and having an inlet and an outlet, a superheating coil adjacent the evaporating coil and having an inlet and outlet, the inlets of the respective coils being at 35 a point most remote from the burner and the outlets being at a point nearest the burner, a receiver to which the inlet and outlet ends of the evaporating coil and the inlet end of the superheating coil are connected, and means for forcing fluid through the evaporating coil.

3. In a boiler, the combination of a burner, an evaporating coil comprising a plurality of 50 concentric convolutions adjacent the burner, a superheating coil comprising a plurality of convolutions adjacent the evaporating coil, a preheating coil comprising a plurality of concentric convolutions adjacent the superheating coil, a housing for the burner and coils, a drum outside the housing, means for supplying fluid to the preheating coil at the point most remote from the burner, a discharge connection to the drum from the point 55 of the preheating coil nearest the burner, a connection between the drum and evaporating coil at the point farthest from the burner, circulating means in the last named connection, a connection from the end of the 60 evaporating coil nearest the burner discharg-

ing tangentially into the drum above the two first named connections, and an intake connection from the top of the drum to the part of the superheating coil most remote from the burner.

4. In a steam generator, the combination of separate preheater, evaporator, and superheater coils surrounding a burner, a casing for the coils and burner, a drum outside the casing, a connection outside the casing between the preheater and drum, a connection outside the casing between the lower part of the drum and evaporator, a pump in said connection for forcing the water through the evaporator, a connection outside the casing from the other end of the evaporator to the top part of the drum for returning a mixture of water and steam to the drum, and a connection outside the casing from the top of 75 the drum to the superheater coils.

5. The combination with means forming a combustion chamber having upper and lower gas confining means in horizontal planes, of means for introducing a combustible mixture into said combustion chamber through one of said planes substantially centrally of said plane and for directing the products of combustion in their travel to the exit at the other plane to cause them to pass laterally through said chamber throughout substantially the entire extent between said two planes, a steam generator composed of tubes formed in coils which are vertically and horizontally spaced apart and surround 90 a central space and are located between and extend closely adjacent to the horizontal planes defining said chamber so as to be confined within the maximum heating space of the gases and between which coils the gases pass, said tubes comprising evaporator, superheater, and preheater sets of distinct and fixed heating area with the evaporator tubes interposed between the point of greatest heat intensity and the superheater tubes to protect the latter, and means to establish communication between the successive sets of tubes.

6. The combination with a burner having an upright part having lateral openings for the products of combustion, of a boiler, said boiler comprising horizontally spaced, vertical banks of separate evaporator, superheater and preheater tubes in coils, each bank including superposed tiers of coils vertically spaced, and said banks surrounding the burner part and lying in substantially the same horizontal confine therewith, the evaporator bank being nearest the burner part, and the superheater coils located so as to have the evaporator coils between the superheater coils and the fire, and means receiving water from the preheater coils to supply the evaporator coils.

7. The combination with a burner discharging hot gases, of a steam generator com- 130

prising tubes in coils against which the hot gases impinge and between which they pass, a non-evaporative storage and separating drum communicating with the coils, means 5 to isolate the drum from the combustion chamber, and means through which the waste gases are conducted after they pass between the coils so located as to prevent direct contact of said gases with the drum and to insulate the latter by the gases from the cooling effect of the atmosphere.

8. The combination with a burner of a steam generator, comprising preheater, evaporator and superheater tubes in coils, 15 the evaporator coils being located between the burner and superheater coils to protect the latter and increase evaporation in the evaporator coils, means for feeding water to the preheater coils, a storage and separating drum, means whereby the evaporator coils receive the supply of water which has passed through the preheater coils and also receive water from the drum additional in quantity to that received from the preheater 20 to thereby increase the heat absorbing capacity of the evaporator coils and their protecting capacity for themselves and the superheater coils, said superheater coils having communication with the drum to receive 25 steam therefrom, and conducting means for the hot stack gases surrounding the drum to thereby protect the latter from the cooling effect of the atmosphere.

9. The combination with a burner dis-

charging gases horizontally therefrom, of a 35 steam generator composed of separate, horizontally spaced vertical banks of evaporator, superheater and preheater tubes in coils, each bank comprising superposed separated helical coils lying within horizontal confines with and 40 surrounding the burner, the evaporator coils being between the burner and the superheater tubes to protect the latter from the heat, a storage and separating drum storing a quantity of water which is additional 45 to that fed through the preheater tubes, said superheater tubes having communication with the drum to lead steam therefrom, said evaporator tubes having both outlet and inlet communication with said drum, means to 50 conduct the water which has passed through the preheater tubes to the evaporator tubes and means to supply through the evaporator tubes a quantity of water from the drum additional to the quantity of water which has 55 been fed from the preheater tubes to thereby increase the heat absorbing capacity of the evaporator tubes over that provided by the amount of water therein received from the preheater tubes, and also further to protect 60 said superheater tubes by increasing said heat absorbing capacity, and to increase the rate of steam generation in said evaporator tubes.

In testimony whereof we affix our signatures.

CHARLES A. FRENCH.
GUSTAF W. ENGSTROM.
